UNITED STATES PATENT OFFICE

2,150,911

ROLLING MILL HOUSING

Everett Chapman, Coatesville, Pa.

Application August 31, 1934, Serial No. 742,308
Renewed June 9, 1938

18 Claims. (Cl. 80—55)

My invention relates to rolling mill housings, and one object of my invention is to provide a structure completely resistant to breakage and capable of withstanding the stresses which may be set up in the operation of structures of this type.

A further object of my invention is to provide a housing constructed of rolled metal sections which are subsequently welded together into a unitary structure.

Another object of my invention is to provide simple and efficient supporting means for antifriction bearing blocks which engage the neck ends of the rolls.

And a further object of my invention is to provide a mill housing structure in which the notched supporting means for the antifriction bearing blocks engaging the roll necks are elastically separated from the main load-resisting members of the mill housing. In other words, I have provided main load-resisting members which are a separate elastic entity.

These and other features of my invention are more fully set forth hereinafter; reference being made to the accompanying drawings, more or less diagrammatic in character, in which:

Figure 1 is an elevation of a rolling mill housing within the scope of my invention.

Fig. 2 is a plan view of the same.

Fig. 3 is a sectional plan view on the line III—III, Fig. 1.

Fig. 4 is an edge view looking in the direction of the arrow a, Fig. 1, and

Fig. 5 is a vertical sectional view on the line V—V, Fig. 1.

My improved structure comprises a U-shaped element 10 of rolled metal which is bent to the form illustrated in Fig. 1 and becomes the main load- or thrust-resisting element of the housing. It also provides the space receiving the ends or necks of the upper and lower rolls A and B, respectively.

To form the sides and bottom-connecting portion of the housing frame which support the element 10, I provide the substantially U-shaped plate sections 11 which are spaced apart laterally and are welded at x to the U-shaped portion 10, as clearly illustrated in Figs. 1 and 3. At the sides of the frame, these sections may be separated, as illustrated in Figs. 2 and 3, although they may be boxed, if desired.

At the upper end of the housing frame, the usual nut or threaded element 12 for the reception of the adjusting screw for the upper roll may be provided, and this member is preferably in the

form of a single casting. It may be provided with depending projections 15 at its sides which are welded at y to the upper ends of the U-shaped section 10, and it will be understood, of course, that the side plates 11 are welded to the ends of the member 12 at x in the same manner that they are welded to the U-shaped section 10.

The side plates 11 are provided with the usual supporting feet 16 which may be welded thereto and, by preference, spacing or the braces 17 are placed over the same at their inner sides between the plates 11 and welded in place. The lower part of the housing structure is preferably of box-like form, as illustrated in the sectional view Fig. 5, including a semicircular strap member 18 which underlies the curved lower portion of the side plates 11 of the housing and is welded thereto and to the feet 16.

Within the space defined by the U-shaped member 10 and the nut or threaded element 12 secured to the upper ends of the same, provision is made for supporting the reduced ends or necks a and b of the upper and lower rolls A and B. The walls of the member 10 forming this space have been machined to exact parallelism, with a semicircularly curved lower end. This lower end receives a liner 20 semicircular in shape, exactly fitting the semicircular lower portion of the U-shaped section 10, with a flange 20^a overlying the edges of the same so as to be retained against lateral displacement. This liner is recessed at 20^b for the reception of the lower bearing block 21 for the neck b of the lower roll B. Side liners 22 are carried by the walls of the U-shaped section 10, which liners are also flanged at 22^a so as to be retained in place, and said liners 22 may rest upon the upper ends of the semicircular liner 20.

The liners 22 are secured to the housing structure by means of bolts 23 passing through said liners and the walls of the member 10, and having heads fitting recesses in said liners, as shown in Fig. 3. The liners 22 are recessed at 22^b and 22^c for the reception of bearing members 24 and 25 of antifriction metal engaging the necks a and b of the respective rolls A and B. The surfaces of the bearing members 24 and 25 conform to the contour of the roll necks b while the surfaces of the bearing members 24, which engage the surface of the neck ends a of the upper roll A, are tangent thereto, permitting rise and fall of the upper roll. The U-shaped member 10 is channeled at 10^a for the reception of the flange 20^a of the semicircular lower member 20, and the flanges 22^a of the side liners 22, as clearly illustrated in Figs. 3 and 5.

As may be understood, the upper roll may rise and fall during the operation of rolling a plate, and the function of the adjusting screw is to insure that the rise of the roll is such as to enable it to roll a plate to the desired gauge in any particular pass and hold it against the plate during the rolling operation.

Heretofore, the great difficulty with rolling mill housings of cast metal has been their proneness to break, the stresses to which the cast metal is subjected being such as to render breakage possible at any point at which the wall has been reduced for the reception of a bearing element for the neck ends of the rolls. In my improved construction, the main load-resisting member 10 of the mill housing is elastically separated from the notched supporting means for the antifriction bearing blocks or members and, while such means are supported by the main load-resisting member 10 for horizontal loads, they do not participate in the vertical loads.

While I have shown and described a more or less specific embodiment of the features forming the subject of my invention, it will be understood that I am not limited thereto and modifications may be made therein within the spirit and scope of the appended claims, without departing from my invention.

I claim:

30 1. In a rolling mill housing, a continuous load-resisting member forming the roll-receiving space, supporting plates therefor disposed in parallelism; said plates flanking and underlying said load-resisting member and welded thereto, upper roll adjusting means surmounting said load-resisting member and disposed between said supporting plates and secured thereto, and a bearing-block receiving element connected to the main load-resisting member in such a manner that it does not elastically participate in the vertical loads.

2. In a rolling mill housing, a continuous load-resisting member forming the roll-receiving space, supporting plates therefor disposed in parallelism; said plates flanking and underlying said load-resisting member and welded thereto, upper roll adjusting means surmounting said load-resisting member and disposed between said supporting plates and secured thereto, and a bearing-block-receiving element connected to the main load-resisting member in such a manner that it is supported by the main load-resisting element for horizontal loads without elastically participating in the vertical loads.

3. In a rolling mill housing, a continuous load-resisting member forming the roll-receiving space, supporting plates therefor disposed in parallelism; said plates flanking and underlying said load-resisting member and welded thereto, upper roll adjusting means surmounting said load-resisting member and disposed between said supporting plates, and a bearing-block-receiving element so connected to the main structure that it is not loaded along its longitudinal axis by the rolling operation.

4. In a rolling mill housing, a continuous load-resisting member of U-shape forming the roll-receiving space, supporting plates therefor disposed in parallelism; said plates being disposed at right angles to and flanking and underlying said load-resisting member and welded thereto, upper roll adjusting means surmounting said load-resisting member and including an element welded thereto and to said supporting plates, and a bearing-block-receiving element connected to

the main load-resisting member in such a manner that it does not elastically participate in the vertical loads.

5. In a rolling mill housing, a continuous load-resisting member of U-shape forming the roll-end-receiving space, supporting plates disposed in parallelism at right angles thereto and flanking and underlying said load-resisting member and welded thereto, upper roll adjusting means surmounting said load-resisting member and including an element welded thereto and to said supporting plates, and a bearing-block-receiving element connected to the main load-resisting member in such a manner that it is supported thereby for horizontal loads without elastically participating in the vertical loads.

6. In a rolling mill housing, a continuous load-resisting member of U-shape forming the roll-receiving space, supporting plates disposed in parallelism at right angles thereto and flanking and underlying said load-resisting member and welded thereto, upper roll adjusting means surmounting said load-resisting member and including an element welded thereto and to said supporting plates, and a bearing-block-receiving element so connected to the main structure that it is not loaded along its longitudinal axis by the rolling operation.

7. A rolling mill housing comprising a main load-resisting member composed of rolled metal sections welded together including a U-shaped member arranged at right angles with respect to the other metal sections, and a notched bearing-block-receiving element carried by and elastically separated from the U-shaped member of said main load-resisting element.

8. A rolling mill housing comprising a main load-resisting member consisting of rolled metal sections substantially U-form in contour welded together including a U-shaped member arranged at right angles with respect to the other metal sections, and a notched bearing-block-receiving element carried by said housing and elastically separated from the U-shaped member of said load-resisting element.

9. In a rolling mill housing, a frame of plate sections welded together, a main load-resisting element secured within said frame, and a bearing-block-receiving element connected to the main load-resisting member in such a manner that it is supported thereby for horizontal loads without elastically participating in the vertical loads.

10. In a rolling mill housing, a frame of plate sections welded together, a main load-resisting element secured within said frame, and a bearing-block receiving element so connected to the main load-resisting element of the housing that it is not loaded axially by the rolling operation.

11. A rolling mill housing comprising a welded structure of rolled metal sections including a continuous U-shaped element forming the roll-end-receiving space, a nut element for the adjusting screw surmounting said U-shaped member and welded thereto, and continuous body plates flanking said U-shaped element and welded thereto; said plates underlying the U-shaped element.

12. A rolling mill housing comprising a welded structure consisting of a continuous U-shaped member forming the roll-end-receiving space, a casting forming a nut element for the adjusting screw surmounting said U-shaped member and welded thereto, and continuous body plates flanking said U-shaped member and welded thereto; said plates underlying the U-shaped member.

13. A rolling mill housing comprising a welded structure consisting of a continuous U-shaped member forming the roll-end-receiving space, a nut element for the adjusting screw surmounting said U-shaped member and welded thereto, continuous body plates flanking said U-shaped member and welded thereto; said plates underlying the U-shaped member, and a bottom plate connecting the portions of the body plates underlying the U-shaped member.

14. In a rolling mill housing, a continuous load-resisting member forming the roll-end-receiving space, supporting plates disposed in parallelism and flanking said load-resisting member and welded thereto, upper roll adjusting means surmounting said load-resisting member and welded thereto and to said supporting plates, and supports for the neck ends of the rolls carried by said continuous load-resisting member.

15. In a rolling mill housing, a continuous load-resisting member forming the roll-end-receiving space, supporting plates disposed in parallelism and flanking said load-resisting member and welded thereto, upper roll adjusting means surmounting said load-resisting member and welded thereto and to said supporting plates, and bearing blocks for contact with the neck ends of the rolls supported by said load-resisting member.

16. In a rolling mill housing, a continuous load-

resisting member forming the roll-end-receiving space, supporting plates disposed in parallelism and flanking said load-resisting member and welded thereto, upper roll adjusting means surmounting said load-resisting member and welded thereto and to said supporting plates, recessed liners removably secured to said load-resisting member, and blocks for contact with the neck ends of the rolls disposed in the recesses of said liners.

17. In a rolling mill housing, a continuous load-resisting member forming the roll-end-receiving space, supporting plates disposed in parallelism at right angles thereto and flanking and underlying said load-resisting member and secured thereto, and a bearing-block-receiving element connected to the main load-resisting member and so supported thereby as to participate in the horizontal loads without elastically participating in the vertical loads.

18. In a rolling mill housing, a frame, a main load-resisting member permanently secured within said frame, and a bearing-block-receiving element connected to said main load-resisting member and so supported thereby as to participate in the horizontal loads without elastically participating in the vertical loads.

EVERETT CHAPMAN.
